REEL MECHANISM

Lorenz Iversen and Franz J. Waldschutz, Pittsburgh, Pa., assignors to Mesta Machine Company, Pittsburgh, Pa., a corporation of Pennsylvania

Application October 30, 1941, Serial No. 417,132

4 Claims. (Cl. 242—78)

This invention relates to reel mechanisms and is herein particularly described as applied to a feed reel for supporting coils of metal strip which are to be unwound for processing, e. g., pickling or cold rolling.

A detailed description of a feed reel appears in our Patent 2,236,971, dated April 1, 1941. As there pointed out, a feed reel should function to support a metal coil for unwinding; to round out any eccentricities in the coil; to pay it out smoothly; and to provide a resistance to the paying-out if, under the circumstances of operation, that seems desirable. It is important that the reel shall engage and center the coil quickly and that there shall be a minimum of time between the paying-out of one coil and the resetting of the reel parts for engagement of the succeeding coil. Our present invention provides these qualities in a construction which is rugged, simple, certain in operation and which requires a minimum of control by the operator.

In the accompanying drawings, illustrating the present preferred embodiment of our invention,

Fig. 1 is a front elevation, partly broken away, of a feed reel;

Fig. 2 is a vertical section through one of the heads of Fig. 1;

Fig. 3 is a section on the line III—III of Fig. 2; and

Fig. 4 is a front elevation, partly broken away, of one of the heads.

The feed reel illustrated in Fig. 1 follows generally the construction of our prior patent and a detailed description thereof is deemed unnecessary on this account. For present purposes, it will suffice to say that it consists of a bed 2 having housings 3 and 4 slidable toward and away from one another thereon as in our prior patent and by known mechanism, as for example that shown in Moxley Pat. 1,990,084, a lifting saddle 5 for receiving and raising coils into position to be mounted in the feed reel and a pair of opposed reel heads 6 and 7 mounted on the housings 3 and 4 respectively. In Fig. 1 the heads are shown in their inwardly adjusted position supporting a coil C.

Figs. 2 to 4 inclusive show the detailed construction of the head 7, and it will be understood that the head 6 is of like construction. The head is carried on a shaft 8, which shaft is carried in the housing 4 and connected to a dynamo electric machine in the manner illustrated in our prior patent. The principal member of the head 7 is a head frame 9. The head frame 9 has a hub 9a

through which it is fixed on the end of the shaft 8 by a key 10 and a nut 11. A spider 12 is fitted over the hub and is provided with a bearing sleeve 13. The spider is slidable axially on the hub, the travel being limited by a shoulder 14 and a stop plate 15. A key 16 prevents relative rotation of the spider 12 and the head frame 9.

In Fig. 2 the solid lines show the spider 12 located against the stop 14. This is the position which the spider occupies when a coil is centered on the head. However, the spider is biased away from the shoulder 14 and toward the stop plate 15 by coil springs 17. These springs are carried by studs 18 threaded into the head frame 9 and fit into pockets 19 in the back of the spider 12. The spider has a coil engaging boss 12a, in consequence of which only the edges of the innermost wraps of the coil are in contact with the reel head.

The spider is radially slotted to provide four sets of guides 20 for chuck members 21. Each of the chuck members has a radially extending guide portion 21a which works in guides 20, a cylindrical coil engaging portion 21b and a conical coil engaging portion 21c. The back of each chuck portion 21a is provided with a pair of ears 22 to accommodate a pin 23. A link 24 is carried on each pin. Each of the links 24 extends inwardly and rearwardly and at its inner end is mounted on a pin 25 carried in the head frame 9. In consequence, relative axial movement of the head frame 9 and the spider 12 causes the chuck members 21 to move radially inwardly or outwardly on the spider.

The guide portions 21a of the chuck members 21 lie behind the coil engaging boss 12a of the spider; see Fig. 3. This eliminates any possibility of the jaws damaging the strip edges.

In Fig. 2 the chuck jaws are shown in their expanded position. This is the position they occupy when the spider is against the stop 14. The dot-and-dash lines in the same view show the position of the spider and the chuck jaws when the spider, actuated by the springs 17, has been moved against the stop plate 15.

The head frame 9 carries a rim shield 26 which minimizes the ingress of foreign matter and forms a safety guard.

The operation of our device is as follows: The housings 3 and 4 are separated and a coil is placed on the saddle 5. At this time there is nothing to prevent the inward movement of the spiders 12 relative to the head frames of the heads 6 and 7, and the springs 17 will have accordingly moved the spiders 12 inwardly against the stop plates

15 and collapsed the chuck jaws 21. The saddle is elevated and the housings 3 and 4 are moved together. The collapsed chucks enter the eye of the coil. The conical portions 21c facilitate this entry. Continued inward movement of the housings 3 and 4 brings the bosses 12a of the spiders 12 into contact with the outer edges of the innermost wraps of the coil, and further inward movement of the spiders 12 is thereby prevented. However, the inward movement of housings 3 and 4 is continued, thus moving the head frames 9 closer to one another against the resistance of the springs 17. This continued movement causes the links 24 to swing from the dot-and-dash line position of Fig. 2 to the solid-line position, thereby expanding the chuck jaws 21. This expansion centers the coil on the reel heads, firmly engages the inner wrap of the coil with the chuck jaws and removes any eccentricity from the coil. The coil is then paid out for processing, the shafts 8 serving either to drive or retard as may be desired. The strip feeds smoothly from the reel, since the heads engage the edges of the innermost wraps only. On the paying out of the innermost wraps of the coil, the bosses 12a are disengaged from the strip and the restraint on the spiders 12 is thereby removed. The springs 17 thereupon function to advance the spiders against the stops 15 and collapse the chuck jaws.

As will be seen from Fig. 2, the links 24, when the chuck is in the expanded position, lie at an angle to the axis of rotation of the head approximating a right angle. In consequence, they have a powerful toggle-like action which insures the rounding out of the coil. On the other hand, when the time comes for the springs 17 to collapse the chuck, the linkage provides substantially the maximum mechanical advantage for starting the inward movement of the chuck jaws. In consequence, there is no danger of the springs 17 failing to overcome the initial friction, and the chucks are collapsed smoothly and with certainty.

We have illustrated and described a present preferred embodiment of our invention. It will be understood, however, that this is by way of illustration only and that the invention may be otherwise embodied within the scope of the following claims.

We claim:

1. A reel comprising a rotatable head, means for moving the head axially toward a coil of material to be engaged and supported, a spider associated with the head and movable axially relatively thereto but fixed against rotary movement

5 relatively thereto, means biasing the spider toward the point of coil engagement, radially extending guides on the spider, chuck jaws for engaging the eye of the coil, the jaws being mounted in the guides on the spider and only inwardly-and-outwardly movable therein, and means for expanding the chuck jaws upon relative axial movement of the head and the spider toward one another.

10 2. A reel comprising a rotatable head, means for moving the head axially toward a coil of material to be engaged and supported, a spider associated with the head and movable axially relatively thereto, means biasing the spider toward the point of coil engagement, chuck jaws for engaging the eye of the coil, the jaws being mounted on the spider and inwardly-and-outwardly movable thereon, and links connecting the chuck jaws and the head and effective for causing movement of the chuck jaws upon relative axial movement of the head and the spider.

15 3. A reel comprising a rotatable head, means for moving the head axially toward a coil of material to be engaged and supported, a spider associated with the head and movable axially relatively thereto, means biasing the spider toward the point of coil engagement, chuck jaws for engaging the eye of the coil, the jaws being mounted on the spider and inwardly-and-outwardly movable thereon, and links connecting the chuck jaws and the head and effective for causing movement of the chuck jaws upon relative axial movement of the head and the spider, the links lying at an angle approximating a right angle to the axis of rotation of the head when the chuck jaws are expanded.

20 4. A reel comprising a rotatable head, means for moving the head axially toward a coil of material to be engaged and supported, a spider associated with the head and movable axially relatively thereto, the spider having a coil-edge engaging face, means biasing the spider toward the point of coil engagement, radially extending guides on the spider, chuck jaws mounted in the guides and projecting beyond the coil-edge engaging face of the spider, the chuck jaws being inwardly and outwardly movable relatively to the spider but fixed against axial movement relatively thereto, and means for expanding the chuck jaws upon axial movement of the head and the spider toward one another.

LORENZ IVERSEN.
